ABSTRACT

A method for sewing a seam in continuous large segmented surface material subjected primarily to forces directed inward and perpendicular to the surface and the product thereof are presented. The most severe seam stresses in a continuous segmented surface material subject to force directed inward and perpendicular to the surface are perpendicular to the applied force at the seams. The product of the present invention includes lap seams between adjacent surface segments where said seams are subject to great stress when the surface is subject to a force directed inward and perpendicular to the surface.

METHOD OF SEWING A SEAM AND PRODUCT THEREOF

This application is a continuation in part of a previously filed Application by the same inventor of the above title, filed Feb. 17, 1969, with a Ser. No. of 799,806 now abandoned.

BACKGROUND OF THE INVENTION

1. Field of the Invention

The present invention relates to a method for sewing a combination comprising three seams in continuous large surface material of a body subjected primarily to forces against said surface directed inward and perpendicular to said surface.

2. Description of the Prior Art

Continuous segmented surface material subjected primarily to force directed inward and perpendicular to the surface have been in limited specialized use for many years. One example of said material is a forced air leakable container. Forced air leakable containers more than 50 feet high can be animated by varying the rate at which air is pumped therein. The seams of such a container may be subjected to a separating stress which tends to pull said seams apart. For this reason, the seams must be very strong.

There are two basic types of seams, the lap seam and the butt seam. The lap seam is inherently much stronger than the butt seam. Accordingly, the lap seam would be more desirable for joining the segments of surface material subject to a separating stress. Unfortunately, the lap seam is more difficult to sew than the butt seam.

When large segmented surfaces are sewn together by machines, prior art methods of sewing lap seams can be applied only with difficulty because of the large quantities of material which must be handled and sewn. If used, prior art methods require excessive amounts of labor thereby greatly increasing the costs of said large segmented surfaces. For example, the prior art includes methods utilizing additional material, generally having a triangular cross section, which is presewn. The additional material is then sewn between adjacent segments of the surface material and internal segment dividers. Unfortunately, these methods require additional material, additional handling, and a large quantity of individual seams between each segment.

Seams also break because of weakness in the material sewn. Accordingly, it is an advantage to have a double thickness of material at each highly stressed seam.

SUMMARY OF THE INVENTION

A method of sewing seams in continuous segmented surface material of a body subject to forces against said surface directed inward and perpendicular to said surface and a product of said method are presented. The method utilizes material which may be doubled over and is sewn together by lap seams to form a segmented body. The method simplifies the sewing of groups of seams in that no material other than the segments required for surface material, the material coupling the segments and the internal segment dividers are required for said seams and, accordingly, the required number of individual seams is minimized.

There are two main types of seams, lap seams and butt seams. Lap seams are inherently stronger than butt seams, but for many applications, lap seams are more difficult to sew.

A segmented forced air leakable container may be fabricated from a series of segments each joined by sewn three seamed triangular material to the adjacent segment and an internal segment divider. One example of such a container comprises a series of long segments 38 inches wide, 25 inches high and more than 20 feet long.

Coupling material the length of the segment and above twelve inches wide is folded over so that one of the long edges is on top of the other long edge. The long edge of the top of the last segment is then caused to overlap the two edges of the 12-inch wide material by approximately 1 inch. For added strength, the edge of the segment may be folded over or under so as to present double thickness material. The two edges of

the 12-inch wide material are then sewn to the edge of the segment by a lap seam.

Approximately one-third of the way down and around the 12-inch wide material, the edges of which have been sewn together, the 12-inch wide material is pinched together parallel to the sewn seam for a width of about 1 inch. The pinched together inch of the 12-inch wide material is then caused to overlap about one inch of the edge of an internal segment divider. The edge of the segment divider may be folded over to form a double thickness, greater strength, 1-inch wide edge. The pinched together 1-inch wide thickness of the 12-inch wide material is then sewn by a lap seam to the 1-inch wide edge of the segment divider. The segment divider is attached to the bottom of the segmented body by means known to the art.

The 12-inch wide material has, at this time, been sewn by parallel lap seams to the edge of the last segment of the forced air leakable container and to the top edge of the last internal segment divider of the forced air leakable container.

The 12-inch wide material is then pinched together along a width of about 1 inch parallel to the two seams previously sewn and about one-half the way between the two seams. One inch along the edge of the next segment is then caused to overlap the folded together 1 inch of the 12-inch wide material. The edge of the next segment may be folded over or under to give the added strength of double thickness material. The 12-inch wide material and the edge of the next segment are then sewn together by a lap seam. When the segment is inflated with forced air, the 12-inch wide material assumes the cross sectional shape of a triangle attached to each of three adjacent pieces of material by lap seams. For most purposes, a suitable cross section of the twelve inch wide material is an equilateral triangle shaped segment coupler, as described herein. For certain purposes, the segment coupler may be given the cross sectional shape of other triangles, geometric shapes other than triangles, or geometrical shapes which are a function of the forces impinging upon the segmented body.

An indefinite number of segments of indeterminate length can be sewn together by the present method. The internal corner of the triangle is sewn to the top surface first, thereby permitting easy access to said material by said sewing machine. The internal segment divider is then sewn to the apex of the triangle, again permitting easy access even though the internal corner has previously been sewn. If another segment is to be added, the top surface of the adjacent segment is then sewn to the exterior corner of said triangle, thereby permitting easy access for the sewing of all individual seams. The top surface of all segments is identical with one exception. The first edge of the top surface of the end segments is sewn only to the edge of the container by a lap seam.

While the example described herein has been described as being of a specific size, the description of the size of the segmented body, the segments and the 12-inch wide material connecting the segments was included only to permit the reader to visualize the example. The method described herein, while it is most useful when fabricating large segmented bodies may also be utilized to fabricate small segmented bodies. The invention described herein may also be utilized to sew curving seams. A particular order of sewing the seams is described herein so that the reader might easily understand what is being done. It will be obvious to those skilled in the art that the order in which the seams are sewn may be varied. While the two edges of the triangular shaped material are described herein as sewn to the top of the last segment of the segmented bodies, it is obvious that the two edges of the 12-inch wide material could easily be sewn to the internal segment divider or the next segment. While the three edges of the internal segment divider, the previous segment and the next segment are coupled here by a 12-inch wide piece of material, it is obvious that three 4-inch wide strips or strips of other width could be used just as easily or the 12-inch wide material could be an extension of the material of either segment surface or the internal segment divider. By using separate materi-

al not a part of any segment to couple the several edges, however, it is relatively easy to sew each seam through double thickness material, thereby strengthening the seam. While the present application describes connecting 12-inch wide material which has a cross section similar to an equilateral triangle when the segmented body is inflated, more than three edges could be sewn by lap seams to the same piece of material by the method described herein and the cross section of the connecting material could take the form of two dimensional geometric figures could be a function of the forces exerted upon the segmented body and could vary along the length of the various seams.

DRAWING SUMMARY

Reference should be made at this time to the following detailed description which should be read in conjunction with the following drawings:

FIG. 1 is a three-quarter view illustrating a continuous large segmented surface subjected primarily to force from the exterior normal direction; and

FIG. 2 is a side view of an example of coupling material sewn according to the present invention.

DETAILED DESCRIPTION

A segmented forced air leakable container may be fabricated from a series of segments each joined by sewn three seamed triangular material to the adjacent segment and an internal segment divider. One example of such a container comprises a series of long segments 38 inches wide, 25 inches high and more than 20 feet long. Other examples have different dimensions.

Reference should be made at this time to FIG. 1 which illustrates a segmented container 10 comprising a series of segments 12 joined together at a surface 13 by coupling material 14 and internal segment dividers 16. Coupling material 14 joins two adjacent segment surfaces to each other and to an internal segment divider 16 perpendicular to the surface 13 by at least three individual seams. Containers such as containers 10 are particularly useful as forced air leakable containers. Segmented containers 10 may be subject to a variety of forces. For certain applications, the primary forces exerted upon a segmented surface of a container are from the exterior directed inward perpendicular to the segmented surface as illustrated by force vector 18.

The force vector 18 presses down on the surface 13 of the container 10 causing the segments 12 to tend to separate at the seams 14 as illustrated by stress vectors 20. If the force 18 is great, severe stress is imposed on the adjacent seams 14 of the container 10 causing separation if the seams 14 are not very strong.

There are two basic types of seams, the lap seam and the butt seam. The lap seam is inherently much stronger than the butt seam. Accordingly, the seams joining segments 12 should be lap seams. Unfortunately, the lap seam is more difficult to sew than the butt seam and this difficulty is increased geometrically as the size of the container to be sewn increases.

Reference should be made at this time to FIG. 2 which illustrates a side view of one surface 30 of a three-dimensional body, said surface 30 comprising two segments 34, 35 joined to an internal segment divider 36 and to each other by a 12-inch wide piece of coupling material 32 which is as long as the two segments. Two surfaces of the coupling material 32 are folded together or transposed at each of the two corners 38, 46 of the apex 62 of the triangle. The edges 57, 58, 59 of segments 34, 35 and segment dividers are shown doubled over or under. Doubling of material through which a seam is sewn strengthens the seam. Of course coupling material may be used to couple other material according to the present invention without doubling the edges of all or any of the material to be coupled. The doubled together coupling material is sewn to the surfaces of the segments 34, 35 of the internal segment divider 36 by thread 42, 54, 64 to form a lap seam 40, 48, 56 near each corner of the triangle.

The coupling material 32 is folded over so that one of the long edges 60 overlaps or is on top of the other edge 61 of the coupling material. The long edge 57 of the top of the last segment 34 is then caused to overlap the two edges 60, 61 of the 12-inch wide coupling material 32 by approximately 1 inch. Where added strength is required the edge 57 is folded over or under so as to present double thickness material. The two edges 60, 61 of the 12-inch wide coupling material 32 are then sewn to the edge 57 of the segment 34 by a lap seam 40. Of course, the two edges 60, 61 of the coupling material 32 may be sewn to the segment 35 or the internal segment divider 36 if that is more convenient or some other seam rather than the one formed from the two edges 60, 61 may be sewn first if that is more convenient.

15 Approximately one-third of the way down and around the coupling material 32, the edges 60, 61 of which have been sewn together, adjacent portions of the coupling material are pinched together or juxtaposed parallel to the seam 40 for a width of about 1 inch which width protrudes. The pinched together inch of the coupling material 32 is then caused to overlap about 1 inch of the edge 58 of the internal segment divider 36. The edge of the segment divider may be folded over or under to form a double thickness greater strength 1-inch wide edge 58. The pinched together protruding 1-inch wide thickness of the coupling material 32 is then sewn by a lap seam 56 to the 1-inch wide edge 58 of the segment divider 36. The segment divider 36 may be attached to the bottom of the segmented body 10 by any means known to the art.

20 An indefinite number of segments of indeterminate length can be sewn together by the present method. If another segment 35 is to be added, the edge 59 of the segment 35 is folded under in a one inch overlap 52. The folded under overlap 52 is sewn by thread 54 to the external corner 46 of the seam, coupling material 32 in an individual lap seams, 48.

25 As an inwardly directed force 18 perpendicular to the surface 34 is exerted, separating stresses 20 are applied to the individual seams 40 and 48 of the coupling material 32. Little stress is placed on the individual seam 56 since the surface 34, 35 is pushing downward causing slack in the internal segment 36. The individual seams 40, 48 are severely stressed by the separating stresses 20, but do not separate because they are lap seams, and accordingly are very strong.

30 The greatest stress on the seams is at the lap seams 40, 48. The force exerted through the seam 56 is equally distributed between the seams 40, 48 if the triangle formed by the seam 32 is isosceles and the angles at the corners 38 and 46 are equal. Accordingly, an isosceles triangular cross-sectional seam 32 is as strong as an equilateral triangular cross-section 50 seam 32. Since the force exerted through the seam 56 is very small, the invention described herein is effective for many applications even if the triangular coupling material 32 is not isosceles.

35 An indefinite number of segments of indeterminate length can be sewn together by the present method. The internal corner of the triangle is sewn to the top surface first, thereby permitting easy access to said material by said sewing machine. The internal segment divider is then sewn to the apex of the triangle, again permitting easy access even though 60 the internal corner has previously been sewn. If another segment is to be added, the top surface of the adjacent segment is then sewn to the exterior corner of said triangle, thereby permitting easy access for the sewing of all individual seams. The top surface of all segments is identical with one exception. The first edge of the top surface of the end segments is sewn only to the edge of the container by a lap seam.

65 While the example described herein has been described as being of a specific size, the description of the size of the segmented body, the segments and the 12-inch wide material connecting the segments was included only to permit the reader to visualize the example. The method described herein, while it is most useful when fabricating large segmented bodies may also be utilized to fabricate small segmented bodies. The invention described herein may also be utilized to sew curving seams. A particular order of sewing the seams is

described herein so that the reader might easily understand what is being done. It will be obvious to those skilled in the art that the order in which the seams are sewn may be varied. While the two edges of the triangular shaped material are described herein as sewn to the top of the last segment of the 5 segmented bodies, it is obvious that the two edges of the 12-inch wide material could easily be sewn to the internal segment divider or the next segment. While the three edges of the internal segment divider, the previous segment and the next segment are coupled here by a 12-inch wide piece of material, 10 it is obvious that three 4-inch wide strips or strips of other width could be used just as easily or the 12-inch wide material could be an extension of the material of either segment surface or the internal segment divider. By using separate material not a part of any segment to couple the several edges, however, it is relatively easy to sew each seam through double thickness material, thereby strengthening the seam. While the 15 present application describes connecting 12-inch wide material which has a cross section similar to an equilateral triangle when the segmented body is inflated, more than three edges could be sewn by lap seams to the same piece of material by the method described herein and the cross section of the connecting material could take the form of two dimensional geometric figures, could be a function of the forces exerted upon the segmented body and could vary along the length of 20 the various seams. The seam 56 is described as a lap seam even though the material 36 may form a slight angle with the material of the seam 56. It is considered herein that the term lap seam includes those seams part way between lap seams 25 and butt seams which in their characteristics resemble lap seams more than butt seams.

The invention has been described in detail to provide a full public disclosure of two of the particular examples thereof. However, said detailed description is not intended in any way to limit the broad features or principles of the invention, or the 30 scope of the invention claimed. The scope of the invention is limited only by the following claims.

What is claimed is:

1. The method of making a segmented article having opposite faces and divider members extending between said opposite faces and forming the segments using a coupling strip between the panels forming a face of the article and the divider members, including the steps of
  - providing the panels to form the outside faces of adjacent segments;
  - providing a panel to form the divider member between adjacent segments;
  - providing a strip of material to constitute the coupling between adjacent face panels and the divider strip;
  - folding the coupling strip to bring the opposite edges thereof even with one another;
  - folding the edge of a first face panel that is to be secured to the coupling strip to form a first double thickness edge;
  - placing said double thickness upon the overlapping edges of said coupling strip with said panel and said coupling strip 55 extending on opposite sides of the overlap just made and

sewing together said overlapped double thickness edge of the first face panel and the edges of said coupling strip to form a first lap seam;

making a first fold in said coupling strip parallel to said first lap seam in that portion of said coupling strip which is remote from said first face panel with the fold crease positioned approximately one third of the linear distance from one edge of said coupling edge to the other;

folding an edge of said divider member to form a second double thickness edge;

overlapping said second double thickness edge on said first fold with said divider member extending away from said coupling member and sewing together said first fold and said second double thickness edge to form a second lap seam;

making a second fold in said coupling strip parallel to said first and second lap seams with the distance between the fold crease just made from the first fold crease being equal to the distance from the first fold crease to the proximate edge of the coupling strip;

folding the edge of a second face panel which is to be toward said first face panel to form a third double thickness edge;

overlapping said third double thickness edge on said second fold in said coupling strip with said second face panel extending away from said coupling strip and sewing together said overlapping third double thickness edge and second fold in said coupling strip to form a third lap seam; and repeating the above steps as necessary to form the finished segmented article.

2. A seam uniting two adjacent face panels lying in the same plane with a transverse member angularly thereto using a coupling member to unite the edges of said face panels and said transverse member, said seam comprising:
  - a double thickness folded edge of the first face panel overlapping the aligned edges of said coupling member and sewn together in a first lap seam;
  - a double thickness folded edge of the second face panel overlapping a fold in said coupling strip parallel to said first lap seam and spaced therefrom, said double thickness folded edge and said fold being sewn together in a second lap seam;
  - a double thickness folded edge of said transverse member overlapping a second fold in said coupling member parallel to and spaced from said first and said second lap seams, said overlapping double thickness edge and said second fold being sewn together in a third lap seam;
  - each of said first and second face panels and said transverse member extending away from said coupling member; and the distance between said first and said third lap seams being substantially equal to the distance between said second and said third lap seams as measured along the intervening portions of said coupling member, whereby the cross section of said coupling member assumes the shape of an isosceles triangle.
